[57] CLAIM

The ornamental design for a chain link for conveyors, as shown and described.

DESCRIPTION

FIG. 1 is a perspective view of a chain link for conveyors, showing our new design;

FIG. 2 is a side elevation thereof;

FIG. 3 is a front elevation thereof;

FIG. 4 is a top plan view thereof;

FIG. 5 is a bottom plan view thereof;

FIG. 6 is a cross-section thereof, taken along line VI—VI of FIG. 4.

FIG.1.

FIG.2.

FIG.3.

FIG.4.

FIG.6.

FIG.5.
